UNITED STATES PATENT OFFICE

WILLIS STUTSON, OF CHICAGO, ILLINOIS

DOVETAIL

Application filed August 17, 1931. Serial No. 557,519.

My invention relates to dovetails for automobile door construction.

One of the objects of my invention is to provide a dovetail construction in which the wear-resisting parts have anti-friction qualities.

A further object is to provide a dovetail construction which will be inexpensive to manufacture and durable and efficient in use.

10 A further object is to provide such a construction which is made up of relatively few parts.

15 A further object is to provide such a construction in which a single resilient member provides cushioning means for the upper and lower wear-resisting members.

20 A further object is to provide such a construction in which the projecting member of the dovetail is provided with a pocket to receive the yieldingly mounted wear resisting members.

Further objects will appear from the description and claim.

25 In the drawing, in which several forms of my invention are shown:

Figure 1 is a perspective view of the receiving portion of the dovetail;

Fig. 2 is a perspective view of the projecting portion of the dovetail;

30 Fig. 3 is a section on the line 3—3 of Fig. 2;

Fig. 4 is a section on the line 4—4 of Fig. 3;

Fig. 5 is a perspective view of the wear-resisting blocks and cushioning member;

Fig. 6 is a section similar to the section of Fig. 3 showing a modified form of pocket-receiving member;

Fig. 7 is a perspective view of the block of Fig. 6; and

40 Fig. 8 is a section similar to that of Fig. 4, showing a different form of cushioning member and wear-resisting block.

Referring to the drawing in detail, and first to Figs. 1 to 5 inclusive, the construction shown therein comprises a receiving member 1 which may be either on the edge of the door post or on the door frame and a projecting device 2 which may be either on the edge of the post or the edge of the door. As shown, it is on the edge of the door.

50 The receiving construction involves a cut-

out 3 in the sheet material of the edge of the door or post, as the case may be, to enable the projecting member 2 to enter and engage the upper and lower engaging portions 4 and 5 of the sheet metal box 6 secured to the upright 10. If desired, the upper and lower engaging portions might be formed as portions struck in from the material of the upright itself in forming the entering opening.

The projecting device comprises a sheet 60 metal pocket 7 having upper and lower securing flanges 8 and 9 which may be secured to the upright 10 in any suitable manner, as by means of screws or spotwelding. The pocket 7 is provided with upper and lower openings 65 11 and 12, through which the engaging portions 13 and 14 of the wear-resisting blocks 15 and 16 project. These blocks are yieldingly held in operative engageable position by means of a centrally positioned block 17 of 70 cushioning material, as rubber, or the like. It will be seen that this construction enables a single piece of cushioning material to serve both for the upper and lower wear-resisting blocks. These blocks may be made of a material which will have anti-friction properties, such as thermo-plastic material or oil-impregnated material or anti-friction metal.

75 The pocket member itself may be formed of sheet material which may be enameled or nickel plated, as desired. As the wear-resisting blocks—if formed of thermo-plastic material—are of uniform color throughout, any wear on these blocks will not result in any deterioration in appearance.

In use, when the projecting member enters the receiving member, the wear-resisting blocks will engage the wear plates 4 and 5 or portions of the receiving member and the door will thus be centered or positioned with respect to the post in a yielding manner, the central cushioning member being compressed in the manner and to the extent necessitated by the relation of the door with respect to the post.

95 The construction shown in Figs. 6 and 7 is substantially that just described except that the receiving member is offset outwardly to a slight extent, as indicated at 18 and 19, so that the wear-resisting plate or portion ex-

tends outwardly substantially flush with the outer surface of the upright 20, and the wear-resisting blocks 15 and 16 also are broadened laterally, as indicated at 21, so as to extend 5 inwardly to a position substantially flush with the outer face of the outside of the pocket portion of the projecting member.

The construction shown in Fig. 8 is substantially that shown in Fig. 4 except that 10 the cushioning member 17 is made wedge-shaped so that its outer portion is thicker than its inner portion, the wear blocks 15 and 16 themselves being made correspondingly thinner. This enables a thicker piece of rubber 15 to be used which may increase the extent to which the wear-resisting blocks may yield under pressure.

It may sometimes be desirable to make the slope of the plates 5 and 6 slightly less than 20 the slope of the wear portions 13 and 14, thus putting a greater compression on the outer thicker portion of the rubber block than on the thin inner portion.

Further modifications will be apparent to 25 those skilled in the art and I desire, therefore, to be limited only by the prior art and the scope of the appended claim.

Having thus described my invention what I 30 claim and desire to secure by Letters Patent is:

A projecting dovetail construction for use with a recessed receiving construction, comprising a projecting metal pocket having upper and lower openings therein, a cushioning 35 wear-resisting construction comprising upper and lower wear-resisting devices, each having a portion retained in said pocket, and a wear-resisting portion extending through said opening for engaging the receiving device, 40 cushioning means between said wear-resisting devices for yieldingly holding said wear-resisting portions in engaging position, and means outside the space between the wear-resisting devices for securing the dovetail construction to a support whereby the entire body 45 of the cushioning means between the wear-resisting devices acts as a cushion in transmitting pressure from one wear-resisting device to the other.

50 In witness whereof, I have hereunto subscribed my name.

WILLIS STUTSON.
